UNITED STATES PATENT OFFICE.

BENJAMIN CLARK LOVERIDGE, OF DETROIT, MICHIGAN.

PIPE-BENDING TOOL.

Application filed October 21, 1926. Serial No. 143,157.

This invention relates to pipe benders, and relates particularly to hand operated pipe benders.

It is the object of the invention to provide a lever-operated pipe bender having a provision for adapting the device for use upon different sizes of pipes.

Another object is to provide a lever-operated pipe bender comprising jaws for engaging the pipe to be bent, one of said jaws being applicable to the tool in a plurality of positions in which the tool is adapted for handling pipe of different sizes.

In attaining these objects, the invention contemplates terminally mounting upon a lever a pair of jaws, spaced lengthwise of the lever, between which may be inserted a pipe to be bent, one of said jaws being adapted to rock with respect to the other, during use of the tool, and having surfaces which are differentially spaced from the other jaw in two alternative positions of use of said rocking jaw.

These and various other objects are attained by the construction hereinafter described, and illustrated in the accompanying drawings, wherein

Figure 1 is a view in side elevation of the pipe bender operatively engaging a pipe.

Figure 2 is an end view of the same.

Figure 3 is a sectional view taken upon line 3—3 of Figure 2, of the rocking jaw in one position of its use, showing an alternative position of such use in dash lines.

In these views, the reference character 1 designates a body carried by a lever 2. Preferably said body is formed with a socket 1^a which detachably receives an end of said lever.

The end of said body opposite to that which formed with said socket, has spaced integral projections 3 and 4 thereon, the latter being longer than the former and being terminally fashioned to form a hooked jaw 5, spaced from the body 1 and projection 3 in the direction of the axis of the lever 2. The end of said body, which is thus spaced from the jaw 5 forms a fulcrum 6 upon which a jaw 7, paired with the jaw 5, is adapted to rock. The jaw 7 rests substantially midway of its length upon the fulcrum 6 and the jaw-engaging surface of said fulcrum is curved to form an approximate semi-cylinder transverse to the length of the engaged jaw 7, which surface establishes a rocking bearing for said jaw.

To hold the jaw 7 in its position of use, a

pin 10 is extended between and carried by the projections 3 and 4, in spaced relation to the fulcrum member 6 and said pin is passed through an over-sized opening 11 formed in the jaw 7, transversely of its length. Said pin is preferably headed at one end, as indicated at 12 and has its other end split lengthwise as indicated 13, the split end portions being sufficiently spread to yieldably hold the pin in place. Each end of the jaw 7 has a pair of flanges 14 projecting oppositely laterally and the two end flanges at one (or the other) side of said jaw will embrace the projection 4 in any operative position of the jaw on the body 1 to compel rocking of the jaw with the lever, in whichever direction the latter may be swung.

When the rocking jaw is applied as shown in full lines in Figure 3, the fulcrum 6 bears upon said jaw within a channel 15 extending transversely of the jaw and formed between pipe seats 16. A pipe 8 may then be engaged between the hooked jaw 5 and the opposing face of the jaw 7 the latter face having pipe receiving channels 17 in its end portions, which increase gradually in depth as they extend to the opposite ends of the jaw.

When the position of the jaw 7 is reversed, as indicated in dash lines in Figure 3, the face of said jaw having the channels 17 seats on the fulcrum member 6, substantially midway of the length of said face and the pipe seats 16 now project toward the hooked jaw 5 and reduce the space between the two jaws 90 so that a relatively small pipe such as is indicated at 9 may be operatively engaged.

Preferably the pipe seats 6 are formed with pipe engaging channels 18 which increase in depth gradually from the inner to 95 the outer edges of said seats.

The channels 17 and 18 when receiving a pipe which is being bent, insure a considerable area of contact between the rocking jaw and the pipe, so as to minimize the possibility of the pipe being dented by said jaw.

In the use of the described tool, the pipe to be bent is first firmly secured in a vice or the like (not shown). The disclosed tool is then applied, preferably at a point adjacent to the vice, the jaws 5 and 7 being oppositely engaged with the pipe. The lever 2 is now swung in the direction in which the pipe is to be bent, causing the jaw 6 to bear at one of its ends upon the pipe and bringing the opposite 110 end portion of the jaw 7 into engagement with the other side of the pipe. Responding

under powerful leverage to these reversely acting pressures, the pipe will be slightly bent. The tool may now be shifted slightly lengthwise of the pipe and the described bending operation repeated, and by further repetitions, the curvature of the pipe may be increased to any desired extent.

It is to be noted that the bending operation places no strain upon the pin 10, which serves merely to maintain the jaw 7 in assembled relation with the remaining parts of the tool.

Having thus described my invention, I claim:

1. A pipe bender comprising a body having provision at one end for engagement by a lever, a projection from the other end of said body hooked to form a pipe-engaging jaw, and a co-acting rocking jaw fulcrumed between said hooked jaw and body and reversible to vary its spaced relation to said hooked jaw.

2. A pipe bender comprising a body rounded at one end to form a fulcrum, a projection from said end hooked to form a pipe-engaging jaw, a coacting jaw adapted to be mounted to rock on said fulcrum member, and having opposite faces for seating upon said member in alternative posi-

tions of said jaw, said jaw being differentially spaced from said hooked jaw in said positions. 30

3. A pipe bender comprising a body having one of its ends fashioned to form a fulcrum member, a projection from said end hooked to form a pipe engaging jaw, and a co-acting rocking jaw having opposite faces engageable with said fulcrum member in alternative positions of said jaw, one of said faces being transversely channeled to receive said fulcrum member whereby the two jaws are differentially spaced in said positions. 35

4. A pipe bender comprising a body having at one end a pair of spaced projections, one of which is hooked in spaced relation to said end to form a pipe engaging jaw, said body being rounded between said projections 45 to form a fulcrum bearing, a rocking jaw engaging upon said fulcrum bearing between said projections and co-acting with the hooked jaw to engage a pipe, the surface of said rocking jaw engaging said fulcrum member being substantially flat, and a retainer member for said rocking jaw extending freely through said jaw and terminally mounted in said paired projections. 50

In witness whereof I hereunto set my hand.
BENJAMIN CLARK LOVERIDGE.
